UNITED STATES PATENT OFFICE.

FRANK ROWNTREE MACHIN, OF LONDON, ENGLAND.

VARIABLE ELECTRIC CONDENSER.

Application filed November 7, 1925, Serial No. 67,543, and in Great Britain August 26, 1925.

This invention relates to operating mechanism for variable electric condensers, moving coil holders, variometers and like tuning and adjusting devices for radio receiving or other apparatus in which the position of a movable member has to be finely adjusted.

The principal object of the invention is to provide operating mechanism, having a rotary operating member which can be rotated directly by hand for relatively coarse adjustment and can also be rotated through speed reduction gear for relatively fine adjustment.

15 A further object of the invention is to provide operating mechanism capable of being applied to existing condensers to enable a "vernier" or fine adjustment to be obtained without the necessity for providing an independently movable "vernier" condenser plate.

Further objects of the invention are to provide operating mechanism for variable electric condensers and other tuning and adjusting devices having "vernier" adjustment which is simple and compact and which is free from backlash and other evils which usually attend the use of reduction gearing.

30 Preferred embodiments of the invention are illustrated in the accompanying drawings in which:—

Figure 1 is an elevation partly in section of a variable condenser provided with operating mechanism constructed according to one form of the invention.

Figure 2 is a section on the line 2—2 of Figure 1.

Figure 3 is a view similar to Figure 1 of a condenser provided with operating mechanism constructed according to another form of the invention, and,

Figure 4 is a cross section through operating mechanism similar to that shown in Figures 1, 2 and 3, provided with additional reduction gearing for use when exceptionally fine adjustment is required.

Referring first to Figures 1 and 2, the condenser 1 is of a well known type comprising fixed plates 2 and movable plates 3 mounted on a rotary spindle 4 which projects through a hole in a panel 5, to which the condenser 1 is secured in any usual or preferred manner.

55 The end of the spindle 4 which projects through the panel, carries an operating

handle 6 which is not fixed to the spindle but is rotatably mounted on a rotary operating member 7, which is screwed on to the end of the spindle 4. The member 7 is 60 accommodated in a cylindrical recess in the handle 6, which is held in position by being screwed to a dial 8 engaging over a reduced cylindrical portion 9 of the member 7 and abutting a shoulder 10 formed on the 65 latter.

The rotary operating member 7 consists of a hollow cylinder, open at its upper end and formed with a pair of helical slots 11 which are engaged by pins or bars 12, which 70 extend through the slots 11 and engage at their outer ends in longitudinal grooves 13 formed in the inner walls of the handle 6.

The inner ends of the pins 12 are secured to a nut 14 screwed on a rotary spindle 15 which projects through a bearing aperture in the upper wall of the handle 6 and carries an operating handle or knob 16 of 75 smaller diameter than the handle 6.

The dial 8 is held frictionally in adjusted 80 position by means of a spring 17 which in the example shown is clamped against the panel 5 by means of the usual fixing bush 18 which clamps the condenser to the panel.

The operation is as follows:— 85

For coarse adjustment of the condenser, the handle 6 is rotated directly by hand and the operating member 7 rotates with the handle by reason of the fact that these members are connected together by the 90 pins 12.

When it is desired to effect a fine adjustment, the knob 16 is rotated so that the spindle 15 is rotated in the nut 14 with the result that the latter is traversed along the 95 spindle. As the ends of the pins 12 are guided in the grooves 13 in the handle 6, the axial movement of these pins causes the operating member 7 to be partially rotated in the handle 6 with the result that the 100 spindle 4 of the condenser is rotated, the handle 6 being held against rotation by the action of the spring 17. The rotary movement of the member 7 is, however, much slower than that of the knob 16 and this 105 enables very fine adjustment of the positions of the plates 3 to be effected.

The construction shown in Figure 3 is exactly similar to that shown in Figures 1 and 2 except for the fact that the spindle of the 110 condenser is plain instead of being screwed and is frictionally gripped in a bore in the

member 7 whilst the spring 17 is clamped to the dial 8 by a collar fixed to the part 9 of the member 7.

In the construction shown in Figure 4, the 5 operating handle 6 which is mounted on an operating member (not shown) in the same way as the handle 6 shown in Figures 1 and 3, is provided with an additional speed reduction device comprising an ebonite sleeve 10 19 disposed in a groove or recess in the wall of the handle 6 and pivoted to the wall by means of a pin 20. The sleeve 19 carries a spindle 21 provided with a handle 22 and formed with a worm 23 meshing with a 15 worm wheel 24 which is disposed between the member 7 and the upper wall of the handle 6 and is secured to the spindle 15.

The spindle 15 is provided with an operating knob (not shown) similar to the 20 knob 16 shown in Figures 1 to 3 and operates in the same manner as the spindle 15 shown in Figures 1 to 3. The sleeve 19 is normally rocked in a clockwise direction from the position shown in Figure 4 so that 25 the worm 23 is disengaged from the worm wheel 24 thus allowing the spindle 15 to be rotated directly by means of its operating knob. When exceptionally fine adjustment of the movable condenser plates is desired 30 however, the sleeve 19 is moved into the position shown in Figure 4 in which the worm 23 meshes with the worm wheel 24 and the shaft is then rotated through the worm wheel by rotating the handle 22.

35 In order to facilitate accurate adjustment, the operating member 7 may carry a pointer 25 (Figures 1 to 3) which projects through an opening in the cylindrical wall of the handle 6 and moves over graduations 26 on 40 the dial 8. When the additional speed reduction device shown in Figure 4 is used the flange 27 of the handle 22 may carry graduations which are read against a mark on the flange 28 of the sleeve 19.

45 Any of the operating devices described above can readily be applied to existing condensers or other tuning or adjusting devices by screwing or otherwise securing the rotary operating member 7 to the operating spindle 50 of the condenser or other device. In order to enable the knob 16 to be rotated without disturbing the handle 6, it is necessary to provide a frictional braking device capable of holding the handle 6 when the knob 16 is rotated. This may be done in either 55 of the ways shown in Figures 1 to 3 or in any other convenient manner.

I claim:—

60 1. Operating mechanism for variable electric condensers and other adjusting devices comprising a rotary operating member, a hand actuated member rotatable on said operating member, cam surfaces on said operating and hand actuated members, 65 a sliding member co-operating with said

cam surfaces to cause relative rotation between said operating and hand actuated members, yielding means for holding said hand actuated member in adjusted position, and a second hand actuated member for operating said sliding member. 70

2. Operating mechanism for variable electric condensers and other adjusting devices, comprising a rotary operating member, a handle rotatably mounted on said operating member, a recess in said operating member, a second handle rotatably mounted on said first mentioned handle, a screw spindle fixed to said second handle and projecting into said recess, a nut on said spindle, 75 slots in said operating member, grooves in said handle, said slots and grooves forming two sets of guide surfaces, and pins on said nut projecting through said slots and engaging said grooves, at least one of said sets of guide surfaces being inclined to the axis of the operating member. 80

3. Operating mechanism for variable electric condensers and other adjusting devices comprising a rotary operating member, a handle rotatably mounted on said operating member, a second handle rotatably mounted on said first-mentioned handle, cam mechanism actuated by said second handle for rotating said operating member relatively to said first mentioned handle, a third handle rotatably mounted on said first mentioned handle and speed reduction mechanism for driving said second handle from said third handle. 90

4. Operating mechanism for variable electric condensers and other adjusting devices according to claim 3 wherein said speed reduction mechanism is declutchable. 95

5. Operating mechanism for variable electric condensers and other adjusting devices comprising a rotary operating member, a handle rotatably mounted on said operating member, said operating member being disposed within said handle, a second handle rotatably mounted on said first mentioned handle and having a spindle projecting into said first mentioned handle, cam mechanism actuated by said second handle for rotating said operating member relatively to said first mentioned handle, a worm wheel on said spindle within said first mentioned handle, a worm meshing with said worm wheel and having a spindle projecting from said first mentioned handle and a third handle mounted on said worm spindle. 105

6. Operating mechanism for variable electric condensers and other adjusting devices according to claim 5 including a sleeve mounted pivotally on said first mentioned handle, said worm spindle being journaled in said sleeve. 110

7. Operating mechanism for variable electric condensers and other adjusting devices comprising a hollow cylindrical rotary 115 120 125 130

operating member, a hollow cylindrical handle mounted concentrically on said operating member and enclosing the same, a screw spindle mounted concentrically in said handle and projecting from the same, a second handle mounted on said spindle, slots in said operating member, grooves in said first mentioned handle, a nut on said spindle and

pins on said nut projecting through said slots and engaging in said grooves, said pins 10 co-operating with said slots and grooves for rotating said operating member in said first mentioned handle.

In witness whereof I affix my signature.

FRANK ROWNTREE MACHIN.
